Primary Examiner — Jasmine Mlinarcik*(74) Attorney, Agent, or Firm* — Boudwin Intellectual Property; Tyler Donato; Daniel Brian Boudwin(57) **CLAIM**

The ornamental design for a hat with dual visors, as shown and described.

DESCRIPTIONFIG. 1 is a perspective view of a hat with dual visors.
FIG. 2 is a top plan view thereof.

FIG. 3 is a bottom plan view thereof.

FIG. 4 is a front elevation view thereof.

FIG. 5 is a rear elevation view thereof.

FIG. 6 is a left side elevation view thereof; and,

FIG. 7 is a right side elevation view thereof.

The broken lines in the drawings illustrate portions of the hat with dual visors that form no part of the claimed design. The broken lines immediately adjacent to the shaded areas represent the bounds of the claim and form no part of the claimed design.

1 Claim, 6 Drawing Sheets(56)
